UNITED STATES PATENT OFFICE

171,523

HAIR CLIPPER HOLDER

Charles E. Babcock, Pismo Beach, Calif.

Application November 17, 1952, Serial No. 22,329

Term of patent 14 years

(Cl. D86—10)

To all whom it may concern:

Be it known that I, Charles E. Babcock, a citizen of the United States of America and residing at Pismo Beach, in the county of San Luis Obispo, State of California, have invented a new, original, and ornamental Design for a Hair Clipper Holder, of which the following is a specification, reference being had to the accompanying drawing, forming part thereof, in which:

Fig. 1 is a side elevation of a hair clipper holder showing my new design;

Fig. 2 is a front view;

Fig. 3 is a back view, and

Fig. 4 is a perspective view of the holder as seen from the side thereof opposite that shown, in Fig. 1.

I claim:

The ornamental design for a hair clipper holder, substantially as shown.

CHARLES E. BABCOCK.
